HEAT EXCHANGER

Application filed March 2, 1929. Serial No. 343,862.

The invention relates particularly to heat exchangers in which a fluid medium is circulated through a hollow heat exchange element, and one object of the invention is to provide a novel and improved supporting means for such an element adapted to accommodate the relative expansion and contraction of the element and certain parts of the supporting means.

10. Certain features of the invention relate particularly to heat exchangers of the type comprising a casing adapted for the circulation of a fluid medium therethrough and a hollow element mounted in the casing and 15 adapted for the circulation of a fluid medium of a different temperature therethrough. This construction is particularly adapted to be employed in water heaters and condensers. In heat exchangers of this type, on account of the differences in temperature between the element and the casing, relative expansion and contraction occur between said element and the casing. The pipe connections for introducing the fluid medium into the element are attached to the casing, the conduit formed by said connections passing through this casing, and it has been a difficult problem in connection with heat exchangers of this type to support the element within the casing in such a manner as to accommodate this relative expansion and contraction of the casing and the element, and at the same time maintain fluid-tight connections between the parts.

30. Another object of the present invention is to improve the construction and mode of operation of heat exchangers of the latter type and to produce a heat exchanger of this character having improved devices for supporting the element in the casing to accommodate the relative expansion and contraction of the same.

45. Other objects of the invention are to improve the construction of heat exchangers of the latter type referred to above with a view of increasing the efficiency of the heat exchange between the fluid mediums and of rendering certain parts of the heat exchanger readily adjustable to adapt the same for different installations.

With the above and other objects in view, the invention comprises the novel and improved features, constructions and combinations of parts hereinafter described and particularly pointed out in the claims, the advantages of which will be readily understood and appreciated by those skilled in the art.

55. The invention will be clearly understood from the accompanying drawings illustrating the invention in its preferred form and the following detailed description of the constructions therein shown.

In the drawings—

Figure 1 is a view partly in vertical section and partly in front elevation of a heat ex- 65 changer embodying the invention;

Fig. 2 is a sectional view taken substantially on the line 2—2 of Fig. 1;

Fig. 3 is a plan view of the heat exchanger;

Fig. 4 is a detail view in side elevation il- 70 lustrating one of the parts of the heat ex- changer;

Fig. 5 is a sectional view taken substantial- 75 ly on the line 5—5 of Fig. 4;

Fig. 6 is a sectional view taken substantial- 75 ly on the line 6—6 of Fig. 4; and

Fig. 7 is a view in side elevation of the heat exchanger.

80. In the construction illustrated in the drawings of this application, the heat exchanger embodies a casing indicated as a whole at 1 constructed for the reception of a fluid medium and comprising end members or heads 2 and 4 and a central member or jacket 6. This casing is provided at its opposite ends 35 with openings 8 and 10 in the head members, the walls of which openings are preferably threaded to receive pipes through which the fluid medium may be delivered to and discharged from the casing. Each of these 90 openings is adapted to serve either as an inlet or a discharge opening as desired.

95. The member 6 of the casing is provided with openings 12 and 14, the walls of which are also preferably threaded to receive pipes for delivering the fluid medium to and discharging the same from the casing. Each of the openings 8, 10, 12 and 14 may be employed either for the connection of a supply or a discharge pipe and in any installation,

the opening or openings which are not in use may be closed by suitable plugs.

Mounted within the casing is a hollow element indicated as a whole at 15 for the reception 5 of a fluid medium of a different temperature. This element comprises a series of chambered or hollow sections 16 preferably made of sheet metal and arranged in parallel relation, as shown in Figs. 1 and 2. The opposite ends of the sections 16 are connected by devices constructed to provide a passageway or conduit through which the fluid medium may be delivered to and discharged from the several sections. Each of the sections 15 is provided with a pipe fitting 18 having tubular portions 20 passing through suitable openings in the sheet metal of a section 16 and spaced flanges 22 engaging the sheet metal of said sections about said opening 20 within the sections. The sections are connected by rings 24 threaded upon the adjacent tubular portions of the pipe fittings 18.

The sections 16 are preferably made of sheet brass and the rings or collars 24 are preferably made of cast bronze or brass. In order to form a tight joint between each of the rings and the sheet metal of the adjacent section, a washer 26 preferably made of copper, is interposed between each of the rings and the 30 adjacent sections 16.

The element 15 made up by the several sections 16 is mounted within and supported by the casing 1. On account of the difference in temperature between the fluid medium introduced 35 into the casing 1 and the fluid medium flowing through said element, relative expansion and contraction will take place between the element and the casing. To accommodate this relative expansion and contraction, 40 each end of the element is supported upon the casing in such a manner that the casing and element may move relatively to compensate for the relative expansion and contraction of the same. The element, in the construction shown in the drawings, has a four-point support within the casing upon swing supports pivoted to turn upon axes which are fixed with relation to the casing. The devices which support the element upon the 50 casing also preferably constitute pipe connections for delivering the fluid medium to and discharging the same from the element.

Each end of the element 15 is supported upon the casing by means of hollow arms 55 pivoted to the casing and also pivoted to the element. Each of these arms indicated as a whole at 27, comprises a pipe member 28 engaging in a bearing carried by one of the heads of the casing 1 and an arm member 30 60 into which the inner end of the pipe member 28 is threaded. The inner end of each of the arm members 30 is threaded upon the tubular portion 20 of the adjacent pipe fitting 18. The arm members, as well as the pipe members 28, are preferably made of cast

bronze or brass and in order to form a tight joint, a copper washer 26 is preferably inserted between the inner face of the arm member and the adjacent face of the outside section 16.

This construction provides a fluid-tight bearing between the inner end of each of the arms and the adjacent pipe fitting 18, and at the same time enables the arm to turn readily with relation to the pipe fitting. The 70 threads connecting the adjacent pipe fitting 18 and the arm member 30 are of relatively low pitch and the turning movement of the arm member upon the pipe fitting produced by the relative expansion or contraction of the casing 1 and the element 15 is not sufficient to allow any leakage between the arm and the element. The pipe member 28 of each pivoted arm is arranged to rotate in a corresponding bearing on the casing 1, this bearing being constructed so as to provide a fluid-tight joint between the arm and the casing. To this end, the casing about each pipe member 28 is provided with outer and inner 80 beveled surfaces with which rings 36 and 38 surrounding the pipe member and having correspondingly beveled surfaces are respectively arranged to engage. The ring 36 is interposed between the outer beveled surface on the casing and a shoulder on the pipe member 28, and the ring 38 is interposed between the inner beveled surface on the casing and the outer face of the arm member 30. With 90 this construction, the pipe member 28 may be threaded into the arm member 30 with sufficient tightness to prevent the leakage of fluid from the casing 1 about the pipe member 28 without interfering with the rotation of the arm 27 within the bearing on the casing. The casing is preferably made of cast bronze 100 or brass and the rings 36 and 38 are preferably made of steel which has a much lower coefficient of expansion than brass, when heated. The contact of steel with brass enables tight joints to be secured without undue friction.

With the above construction, each end of the element within the casing 1 is supported by two hollow swinging arms, each pivoted to the casing and to the element. Each of these arms is pivoted to turn about the axis of one of the pipe members 28 and is also pivoted to the element to turn relatively thereto about the axis of the adjacent pipe fitting 18. This construction enables each end of the element to move readily relatively to the casing longitudinally of the casing. The swinging arms provide pipe connections for delivering the fluid medium to and for discharging the same from the interior of the element.

Each of the pipe members 28 is preferably threaded to receive a pipe for delivering the fluid medium to or discharging the fluid medium from the casing. Preferably, when the device is in operation, only the diagonally op-

posite pipe members 28 are connected up with the delivery and discharge pipes, the other pipe members 28 being then closed by suitable plugs. For example, as shown in Fig. 1, the 5 upper right-hand and the lower left-hand pipe members 28 may be connected up with delivery and discharge pipes respectively and the upper left and lower right-hand pipe members 28 may then be closed. This set-up 10 provides a passage of maximum length for the fluid through the element and also enables efficient circulation of the fluid through the element to be produced.

15 The construction illustrated in this application may be efficiently employed in heating systems in which water is circulated through the element within the casing and steam is introduced into the casing for heating the water during its passage through said element.

20 The steam introduced into the casing may be live steam from a boiler or other suitable source, or exhaust steam from a power plant. Instead of steam, hot water, or both steam and hot water may be introduced into the outer 25 casing. The present construction may be installed in connection with an industrial or domestic heating plant and the steam or hot water, or steam and hot water, may be derived from the boiler of the plant.

30 The central casing member 6 is connected to the heads of the casing so as to enable said central member to be adjusted angularly about the axis of the casing. This enables the

35 positions with relation to the heads, as found necessary or desirable for different installations. This will enable the delivery and discharge pipes for the casing to be located in different positions with relation to the heads.

40 The connection between each of the heads and the central member of the casing also is such as to enable each head to be attached to the casing in either of two positions 180° apart with relation to the central member or other 45 head of the casing.

The central member 6 of the casing is provided at its ends with out-turned flanges 40 which are engaged by out-turned flanges 42 formed on the heads of the casing. Each end

50 of the central member 6 is secured to one of the heads by bolts 44 passing through openings in the flanges 42 on the heads and through slots 46 in flanges 40. The slots in the flanges 40 and the openings in the flanges

55 42 are located so that the central member may be attached to the heads in a number of different angular positions about the axis of the casing. In the construction shown, the bolt holes and slots are equally spaced about the common axis of the heads and the central member.

60 With the above construction, the heads of the casing may be attached to the central member 6 of the casing with the heads in the relative positions shown in Fig. 1, or either

head may be attached to the central member in a position such as that in which the head member would be placed by turning the same about the axis of the casing 180° from the position shown in Fig. 1. This provision for 70 relative adjustment of the head members enables the openings 8 and 10 to be located in different relative positions and may be found of considerable convenience in different installations. 75

Each of the sections 16 of the hollow element are constructed so that the fluid, in flowing through the same, will follow a tortuous path. Each of the sections 16 comprises spaced sheet metal side walls 48 secured together at their margins 50 preferably by welding. In order to provide baffles within these sections, the side walls of the sections are also secured together preferably by welding along the elongated contact areas indicated at 52. These elongated areas are arranged in staggered relation longitudinally of each section, as shown in Fig. 4 so that the fluid, in passing from one end of a section to the other, is forced to follow a tortuous path. 80 These baffles will retard the speed of flow of the fluid through each section of the element and will increase the length of the path of the fluid through the section. The heat exchange between the fluid and the walls of the 85 section will be thereby correspondingly increased. 90

In certain instances, the steam used in heating systems of this character, particularly the exhaust steam from boilers, contains foreign matter, such as oil or carbon particles. It has been found that a large part of this foreign matter may be removed from the steam by causing the steam to pass through relatively small apertures. In the 100 present construction, some of the carbon, oil and other foreign matter from the steam will be deposited on the bodies of the sections 16 which form baffles engaged by the steam during its passage through the casing. In order 105 to remove still more of the oil and foreign matter from the steam, each of the sections 16 is provided with elongated relatively narrow transverse openings 54 preferably extending through the areas along which the side walls of the sections are attached. With this construction, the steam in passing 110 through the casing will pass through these relatively long narrow openings and a considerable part of the oil and other foreign 115 matter will be deposited on the sections 16 during its passage through these openings.

120 Although the invention has been illustrated and described as embodied in a heat exchanger comprising an outer casing and an element mounted within the casing, it is to be understood that certain features of the invention are not limited to this particular form of exchanger, but that they may be embodied in other heat exchangers. 125

It is to be understood that the invention is not limited to the particular construction and arrangement of parts of the illustrated embodiment of the invention, but that the invention may be embodied in other forms within the scope of the claims.

Having explained the nature and object of the invention, and having specifically described a construction embodying the invention in its preferred form, what is claimed is:

1. A heat exchanger having in combination a casing for the reception of a fluid medium, a chambered element mounted within the casing for the reception of a fluid medium of a different temperature, and means for supporting the element within the casing comprising a swing-support pivoted to the casing to turn on an axis fixed with relation to the casing.

2. A heat exchanger having in combination a casing for the reception of a fluid medium, a chambered element for the reception of a fluid medium of a different temperature mounted within the casing, and means for supporting the element within the casing, comprising a member connected to the element and pivoted to the casing to turn on a bearing fixed with relation to the casing.

3. A heat exchanger having in combination a casing for the reception of a fluid medium, a chambered element mounted within the casing for the reception of a fluid medium of a different temperature, and means for supporting the element within the casing, providing a multiple-point support for the element comprising swing-supports connected with the element and pivoted to the casing to turn on axes fixed with relation to the casing.

4. A heat exchanger having in combination a casing for the reception of a fluid medium, a hollow element mounted within the casing for the reception of a fluid medium of a different temperature, and means for supporting the element within the casing comprising a hollow arm pivoted to said casing and to said element and forming a pipe connection for said element.

5. A heat exchanger having in combination a casing for the reception of a fluid medium, a hollow element mounted within the casing for the reception of a fluid medium of a different temperature, means for supporting the element within the casing comprising a hollow arm pivoted to said casing, and a fluid-tight bearing between one end of said arm and said casing and a fluid-tight bearing between the other end of said arm and said element.

6. A heat exchanger having in combination a casing for the reception of a fluid medium, a hollow element mounted within the casing for the reception of a fluid medium of a different temperature, means for supporting the

element within the casing comprising a swinging arm at each end of the element pivoted respectively to the element and to said casing and forming a pipe connection for the element.

7. A heat exchanger having in combination a casing for the reception of a fluid medium, a hollow element mounted within the casing for the reception of a fluid medium of a different temperature, and means for supporting the element within the casing, comprising two hollow swinging arms for supporting each end of the element, a fluid-tight bearing between each arm and the casing, and a fluid-tight bearing between each arm and the element.

8. A heat exchanger having in combination a casing for the reception of a fluid medium, an element mounted within the casing for the reception of a fluid medium of a different temperature, and means for supporting the element within the casing to permit relative expansion of the casing and element, comprising a swinging arm pivoted to the element and to the casing.

9. In a heat exchange device, a heat exchange element for the reception of a heat exchange medium, means for supporting said element comprising a swinging arm to accommodate the relative expansion and contraction of the element and certain parts of the supporting means.

10. In a heat exchange device, a heat exchange element and means for supporting the same, comprising a hollow swinging arm forming a pipe connection for said element and arranged to accommodate by its movement the expansion and contraction of the element with relation to certain parts of the supporting means, and a fluid tight bearing between said arm and the element.

11. A heat exchanger having a casing comprising a head, a hollow heat exchange element mounted in said casing, means secured to the head and connected with said element for conducting a fluid heat exchange medium, a casing body, means for connecting a conduit to said body for the passage of a fluid heat exchange medium of a different temperature, and means for securing together the casing head and body in different positions with relation to each other.

12. A heat exchanger having an outer casing for the passage of a fluid heat exchange medium and comprising relatively adjustable sections, a hollow heat exchange element for the passage of a fluid heat exchange medium of a different temperature mounted in and wholly enclosed by said casing, means secured to one of the sections of the casing and to said element for conducting the latter fluid medium, means for connecting another section of the casing to a conduit for conducting the first fluid medium, and means for securing together the two sections of the

casing in different positions with relation to each other.

13. A heat exchanger, comprising an outer casing for the circulation of a fluid medium, an inner element for the circulation of a fluid medium of a different temperature mounted in the casing and comprising one or more sections each having longitudinal passages arranged in staggered relation longitudinally of the element through which the fluid in said element flows successively, and transverse slots extending through the section between the passages and permitting the fluid in the outer casing to surround the walls of each of said passages.

14. A heat exchanger, having an outer casing for the circulation of a fluid medium and an inner element for the circulation of a fluid medium of a different temperature, said element having sheet metal side walls and interior baffles formed by inwardly bent portions of the side walls for directing the fluid in said element in tortuous paths.

15. A heat exchanger, having an outer casing for the circulation of a fluid medium and an inner element for the circulation of a fluid medium of a different temperature having sheet metal side walls and elongated baffles formed by inwardly bent portions of the side walls and dividing the element into elongated longitudinal passages, the walls of which are substantially surrounded by the fluid medium in the outer casing.

Signed at New York, N. Y. this 27th day
35 of February 1929.
